(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with graphical user interface showing the new design;

FIG. 2 is a second view with a different color of FIG. 1;

FIG. 3 is a third view with a different color of FIG. 1;

FIG. 4 is a fourth view with a different color of FIG. 1;

FIG. 5 is a fifth view with a different color of FIG. 1;

FIG. 6 is a sixth view with a different color of FIG. 1;

FIG. 7 is a seventh view with a different color of FIG. 1;

FIG. 8 is a front view of a second embodiment thereof;

FIG. 9 is a second view with a different color of FIG. 8;

FIG. 10 is a third view with a different color of FIG. 8;

FIG. 11 is a fourth view with a different color of FIG. 8;

FIG. 12 is a fifth view with a different color of FIG. 8;

FIG. 13 is a sixth view with a different color of FIG. 8; and,

FIG. 14 is a seventh view with a different color of FIG. 8.

The broken lines showing a display screen, text, numbers, symbols and portions of the graphical user interface illustrate portions of the article and form no part of the claimed design.
